FIGURE 1 is a left rear perspective view of a calender stack or similar article showing our new design;

FIGURE 2 is a right front perspective view thereof;

FIGURE 3 is a perspective view of a modified form of the calender stack shown in FIGURE 1; with the base shown broken away to indicate undeterminate length; and

FIGURE 4 is a view in perspective of the interior or back side of the calender stack of FIGURE 3, the right stack thereof and the crossbeam being omitted and shown in section, respectively.

The undisclosed end and side of FIG. 3 are substantially the same as the side and end shown.

We claim:

The ornamental design for a calender stack or similar article, as shown and described.
